UNITED STATES PATENT OFFICE.

JOHN SMITH, OF EARLS BARTON, AND FRED RICKS, OF LEICESTER, ENGLAND, ASSIGNEES TO UNITED SHOE MACHINERY CORPORATION, OF PATERSON, NEW JERSEY, A CORPORATION OF NEW JERSEY.

STITCH-SEPARATING MACHINE.

Application filed July 13, 1921. Serial No. 484,367.

To all whom it may concern:

Be it known that we, JOHN SMITH and FRED RICKS, subjects of the King of Great Britain, and residing, respectively, at Earls 5 Barton, in the county of Northampton, England, and Union Works, Belgrave Road, Leicester, in the county of Leicester, England, have invented certain new and useful Improvements in Stitch-Separating Machines; and we do hereby declare the following to be a full, clear, and exact description of the invention, such as will enable others skilled in the art to which it appertains to make and use the same.

15 The present invention relates to stitch separating machines which are adapted to operate upon the tread surface of a boot or shoe bottom to indent the same along the line of a seam, the stitches of which are exposed on the shoe bottom, it may be in a groove thereon. This operation is commonly known as janking-up or chopping-up.

The object of the present invention is to 25 provide a janking-up machine having an improved construction and mode of operation whereby the stitches appearing on the tread surface of a shoe sole may be separated accurately and indented in a uniform 30 and satisfactory manner.

With the above object in view, a feature 35 of the present invention comprises the provision in a janking-up machine of an indenting tool, novel work supporting and guiding means for presenting the tread surface of the shoe to the action of the tool, and means for actuating the tool to cause it to locate the intervals between the 40 stitches, whether the stitches are of uniform or varying length and to feed the work.

By providing means for locating the indenting tool in the stitch intervals, injury 45 to the thread or disfigurement of the stitch crowns is prevented in case a variation or irregularity in the length of the stitches occurs and a shoe bottom having the stitches cleanly marked and accentuated by separating indentations is produced without any special skill or care on the part of the operator.

50 Stitch separating machines adapted to act only upon the outseam stitches appearing

upon the welt of a shoe have heretofore been devised in which means were provided for 55 located the indenting tool in the intervals between the stitches. Such machines, however, are not adapted for operation upon the tread surface of a sole and are incapable of performing the operation of janking-up. It is believed that the machine disclosed in 60 the present application is the first machine in the art by which the intervals between the stitches appearing on the tread surface of a shoe sole can be accurately located and consequently is the first machine in the art by which the janking-up operation can be 65 separately performed in a reliable and satisfactory manner notwithstanding variations or irregularities in the length of the 70 stitches.

Another feature of the present invention comprises the provision, in a janking-up machine, of an indenting tool, and work supporting and guiding means for presenting the tread surface of the shoe to the action of the tool comprising a rigid work rest to engage the tread surface of the sole and a movably mounted work support arranged to engage the welt or upper surface of the 75 projecting sole edge across its full width and support the work against the thrust of the indenting tool. This arrangement of work rest and work support permits the use of an indenting tool which moves a fixed 80 and uniform distance beyond the surface of the work rest in engagement with the tread surface of the sole so that a series of stitch separating indentations of uniform 85 depth and appearance are produced on the sole surface. Preferably the work support which engages the welt or upper surface of the projecting sole edge is yieldingly mounted so as to press the work against the work rest and accommodate shoe soles of different 90 thicknesses. Also preferably means are provided for locking the work support rigidly in position during the indenting 95 stroke of the tool. In the preferred form of the invention hereinafter specifically described, the work support is also mounted so as to be capable of movement in a plane parallel to the tread surface of the sole, and an unyieldingly mounted edge guide is provided against which the edge of the shoe 100 sole may be pressed and by which the shoe

may be guided as it is fed to bring the stitch intervals successively into position to be acted upon by the indenting tool.

In addition to the features above referred 5 to the present invention also consists in certain constructions, combinations and arrangements of parts hereinafter described and claimed, the advantages of which will be obvious to those skilled in the art from 10 the following description.

Referring to the drawings Fig. 1 is a view 15 in side elevation partly in section of a jacking-up machine embodying the several features of the present invention in their preferred form; Fig. 2 is a view in front elevation of some of the parts shown in Fig. 1; Fig. 3 is a plan view showing the upper and lower work supports and gage wheel; and Fig. 4 is a plan view showing somewhat 20 diagrammatically the relative positions of the base, the cam shaft, the treadles and the work supports of the machine.

In the machine illustrated in the drawings the mechanism for actuating the indenting tool to cause it to locate the intervals between the stitches and indent and feed the work is substantially the same as that of the stitch separating and indenting machine designed for operation upon the 25 welt surface of a shoe and fully disclosed in Letters Patent of the United States No. 543,012, granted July 23, 1895, upon the application of John B. Hadaway. Also in the machine illustrated in the drawings the 30 work support which sustains the work against the thrust of the indenting tool is mounted upon a vertical yielding slide which is forced upwardly and rigidly locked in position during the indenting 35 stroke of the indenting tool by mechanism similar to mechanism disclosed in said Hadaway patent.

Referring to the drawings, the indenting 40 tool is indicated at 1 and is clamped in a tool holder 2 which is secured to a tool stock 3. This tool stock is mounted upon the tool carrying frame or lever 4, which is carried by a feed slide and which is acted 45 upon by a spring 5, tending to depress the lever and bring the indenting tool into engagement with the work. The lever which acts upon the tool carrying frame to lift the tool from the work is indicated at 6 and the pressure lever, which acts positively to 50 depress the tool carrying frame and cause the tool to indent the work, is indicated at 7. The lever which actuates the feed slide to impart stitch locating and work feeding movements to the tool is indicated 55 at 8. The parts above described are or may be constructed and arranged to operate substantially as indicated and described in the 60 patent to Hadaway above referred to.

During the operation of the machine on a 65 shoe, the shoe is supported and guided by

a work rest 9 arranged to extend over the tread surface of the sole, a work support 10 arranged to enter the crease between the projecting sole edge and the upper and engage with its upper surface the welt or 70 upper surface of the projecting sole edge, and an unyieldingly mounted edge guide 11 consisting of a rotatable disk supported upon a stud rigidly secured in the work rest 9 and projecting downwardly therefrom so 75 that the edge of the disk which engages and guides the sole edge is located between the work engaging surfaces of the rest 9 and support 10.

The work rest 9 is provided with a single 80 forwardly projecting portion located at the side of the tool toward which the work is fed, there being no portion of the work rest at the side of the tool from which the work is fed to interfere with the feeding 85 of the work so that the stitch separating and indenting operation can be continued close up to the breast of the heel. Effective support is given the work, notwithstanding the absence of an arm on the right of 90 the tool, because the rest 9 can be extended further forward without interference with any parts projecting from the tread face of the shoe.

The work support 10 comprises a plate 95 which is pivotally mounted at its lower ends upon a pivot pin 12 extending between ears 13, projecting from the lower end of a vertically movable slide 14. This plate 100 extends upwardly from its pivot for some five inches at a rearward inclination of about twenty degrees to the vertical when it sweeps in a gradual curve forwardly again so that its upward extremity is more or less in the same vertical plane as its pivot. The uppermost surface of this work support 105 is plane and horizontal so that it is adapted to support the upper or welt surface of the projecting sole edge of a shoe. The uppermost surface of the work support 110 meets the front surface at an acute angle so that a horizontal edge is formed on the front of the uppermost surface, which seats itself snugly in the crease of the shoe. The slide 14 is somewhat similar in construction 115 to the corresponding slide of the machine of the Hadaway patent above referred to, and is pressed yieldingly upward by a spring 15 interposed between the lower end 120 of the slide and a bracket 16 projecting from the machine frame and surrounding a rod 17 secured to the slide 14 and connected at its lower end to a foot treadle as in the machine of the Hadaway patent. The slide 14 is cut away at 18 to admit of the work support 10 swinging rearwardly substantially in a plane parallel to the tread surface of the sole and the work support is 125 normally held in its forward position by a spring pressed plunger 19 housed in the

130

vertically movable slide 14 and acting upon a stud 20 adjustably secured in the work support near its pivotal connection with the slide. Projections 21 on each side of the work support near its upper end limit its forward movement under the influence of the spring pressed plunger by engaging the rearward faces of the cap plates 22 by which the vertically movable slide is guided.

10 Gas heating jets 23 and 24 are provided to heat both the tool and work support as it has been found that there is less likelihood of the work support defacing the already indented welt when it and the surface it contacts are heated.

15 To force the work support upwardly and lock it in position rigidly during the indenting stroke of the indenting tool, mechanism similar to that of the machine of the Hadaway patent is provided comprising the pivotally mounted lever 25 having a block and slot connection at its forward end with the slide 14 and provided at its rear end with ratchet teeth 26 and a cam actuated lever 27 provided with a pawl 28 to cooperate with the ratchet teeth 26 on the lever 25.

20 In Fig. 4 of the drawings an arrangement of treadles is illustrated which is customarily used upon stitch separating machines which are adapted to operate upon the welt surface of a shoe. In the customary operation of such machines the operator stands at one side of the machine, that is to say, with the main shaft 29 extending in a direction away from him and with the work feeding away from him. For this purpose, as illustrated in Fig. 4, the treadle 30, controlling the usual friction clutch by which the machine is put into operation and by which the speed of the machine is controlled, has a foot piece 31 on that side of the base of the machine column at which the operator stands and the foot piece 32 of the treadle controlling the work support 45 is at the right front corner of the base. As it is preferable in operating a janking-up machine for the operator to stand at what is truly the front of the machine the clutch controlling treadle of the machine illustrated in the drawings is provided with a second foot piece 33, as indicated in Fig. 4, close to that of the other treadle but at the corner of the base of the column.

50 The operation of the machine above described will be readily understood without a detailed description thereof. To insert the work in the machine the slide 14 with the work support 10 is depressed, the edge of the shoe sole with the tread surface uppermost is inserted between the work support 10 and work rest 9, the work support is allowed to rise thereby clamping the projecting edge of the sole between the work support and work rest, the shoe is forced 55 rearwardly until the edge of the shoe sole

contacts with the guiding disk 11 and the machine is thrown into operation. The indenting tool is allowed to rest yieldingly on the work, the feed slide is actuated to locate the edge of the indenting tool in a stitch interval, the work support is clamped in position, the indenting tool is caused to be actuated to make an indentation of predetermined depth, the work support is unlocked and the work is fed by the tool. The operator is merely required to hold the shoe in position with the edge of the sole against the edge guide 11 and regardless of variations or irregularities in the stitches appearing on the tread surface of the sole the stitches are separated and indented in an accurate, uniform and satisfactory manner. At the conclusion of the janking-up operation the machine is stopped, the work rest is lowered and the work removed.

25 The object and nature of the invention having been indicated and a specific embodiment of the several features of the invention having been specifically described, what is claimed is:

1. A janking-up machine having, in combination, an indenting tool, a rigid work rest to engage the tread surface of the sole, an unyieldingly mounted guide to engage the edge of the sole, and a work support mounted to move so as to project more or less beyond said guide in a plane parallel to the tread surface of the sole and arranged to engage the welt or upper surface of the projecting sole edge to support the work against the thrust of the indenting tool, said work support being constructed and arranged automatically to adjust itself to varying depths of the welt crease.

2. A janking-up machine having, in combination, an indenting tool, a rigid work rest to engage the tread surface of the sole, an unyieldingly mounted guide to engage the edge of the shoe sole, and a work support yieldingly mounted to move toward and from the work rest and also yieldingly mounted to move in a plane parallel to the tread surface of the sole and arranged to engage the welt or upper surface of the projecting sole edge and support the work against the thrust of the indenting tool.

3. A janking-up machine having, in combination, an indenting tool, work supporting and guiding means for presenting the tread surface of the shoe to the action of the tool comprising a work support arranged to enter the angle between the upper and the projecting edge of the sole and support the sole against the thrust of the indenting tool, and means for heating the work support.

4. A janking-up machine having, in combination, an indenting tool, a rigidly mounted work support to engage the tread surface of the shoe sole, an unyieldingly mounted guide to engage the edge of the

shoe sole, a work support arranged to engage the welt or upper surface of the projecting sole edge and support the work against the thrust of the indenting tool, 5 and a yieldingly mounted slide upon which the work support is pivotally mounted so as to be capable of moving toward and from the work rest with the slide and also with relation to the slide to maintain the sole 10 edge in contact with said guide.

5. A janking-up machine having, in combination, an indenting tool, an unyieldingly mounted guide to engage the edge of a shoe sole, a slide, a work support pivoted 15 to the slide substantially vertically below the indenting tool to swing towards and from the guide thereby to adapt its position to varying characteristics of the work, said support comprising a portion for engaging the welt or upper surface of a sole edge to support the shoe against the thrust of the indenting tool and an arched portion conforming to the bulged part of the upper. 20

6. A janking-up machine having, in combination, an indenting tool, a guide for the edge of a shoe sole, a slide movable towards and from the indenting tool, a work support pivoted to the slide and having a portion for engaging the welt or upper surface 30 of the sole, means for limiting the projection of said work supporting surface in front of said edge guide, and a spring for yieldingly resisting the movement of the work supporting surface towards the guide. 35

7. A janking-up machine having, in combination, an indenting tool, a guide for the edge of a shoe sole, a slide movable vertically towards and from the indenting tool, and a work support having a surface to

enter the angle between the upper and the 40 projecting surface of the welt or sole to support the work against indenting pressure on the tread face of the sole, said support being pivotally mounted on the slide for movement toward and away from the upper, the mounting being at a distance from the tool substantially greater than the maximum depth of a shoe upper whereby the movement of the supporting surface is in 45 planes substantially parallel to the tread surface of the sole. 50

8. Mechanism for converting a stitch separating machine in which the indenting tool is actuated to feed the work away from the operator into a janking-up machine in 55 which the work is fed from side to side of the operator, comprising a work support constructed and arranged to engage a welt or sole edge to hold a shoe with its tread face upward under the tool, and a treadle for controlling the machine and extending to a point with respect to the axis of the machine approximately 90° from the usual controlling treadle. 60

9. A machine of the class described having, in combination, an indenting tool, means for actuating the tool to cause it to locate the intervals between stitches on a shoe sole and to feed the work, a rigid work rest having a single arm arranged at the 70 side of the indenting tool toward which the work is fed to leave the space on the other side of the tool unoccupied for feeding the work close to the heel, and a work support under the tool to hold the work against the 75 rest. 80
